[57] CLAIM

The ornamental design for a foldable solar cooker, as shown.

DESCRIPTION

FIG. 1 is a front elevational view of a foldable solar cooker, showing my new design;
FIG. 2 is a rear elevational view thereof;
FIG. 3 is a side elevational view thereof, the opposite side being a mirror image thereof;
FIG. 4 is a sectional view of the parabolic reflector and pot hanger portion of the design, taken along line 4—4 of FIG. 1;
FIG. 5 is a top plan view thereof; and,
FIG. 6 is a front elevational view of the design in folded condition.

FIG. 1

FIG. 2

FIG. 3

FIG. 4

FIG. 5

FIG. 6
